HOOD FASTENER

Filed March 31, 1926

UNITED STATES PATENT OFFICE

FRANK A. WHITTEN, OF DETROIT, MICHIGAN, ASSIGNOR TO GENERAL MOTORS CORPORATION, OF DETROIT, MICHIGAN, A CORPORATION OF DELAWARE

HOOD FASTENER

Application filed March 31, 1926. Serial No. 93,761.

This invention relates to automobile hoods, and has for its object the production of a simple but efficient means for holding or securing the complementary removable side panels thereof against accidental displacement from the body of the automobile, the invention being particularly adapted for hoods of large heavy engines, such hoods generally being composed of three or four separate panels.

Another object of the invention is to provide a locking device for the side panels of the hood which is adapted to be used in connection with any of the known types of barrel fasteners, the fasteners being carried on the side panels and having an operating mechanism carried in the lower end thereof which is arranged to draw the complementary sections of each side of the hood into retentive engagement with one another.

Another object of the invention is to provide such a locking device that not only positively insures against accidental displacement of the various panels constituting the hood, but at the same time is so arranged as to allow the same to be readily placed upon the frame of the automobile, or removed therefrom.

Another object of the invention is to provide stirrups near the lower end of the hood shelves which are adapted to project through the body of the side panels and engage with a reinforcing rod carried by the bottom marginal edge of the side panel whereby as the side panel is forced into engagement with its adjoining top portion, the side panel is guided inwardly by the said stirrup and firmly pressed against the hood support.

Other objects will appear hereinafter.

In the drawings:

Figure 1 is an elevation of an automobile, embodying a hood and locking device as constructed according to the principle of the invention.

Figure 2 is a fragmentary elevation of the hood support and side panel heated thereon, the view illustrating one embodiment of the invention;

Figure 3 is a sectional elevation of the same;

Figure 4 is a fragmentary elevation of the hood support and the side panel resting thereagainst of another embodiment of the invention; and

Figure 5 is a side elevation of the same. 55 Throughout the various figures, similar parts are designated by similar numerals.

The invention is admirably adapted to be used in connection with the usual three or four piece hoods commonly found only on 60 automobile trucks, although as will be readily apparent as the description proceeds, its use in this particular manner is not to be construed limited thereto.

The automobile A, as illustrated in Figure 1, is a truck chassis, and the hood thereof comprises preferably four complementary panels, the upper panels 6 and the side panels 7, the two upper panels 6 being suitably hinged together. The bottom marginal edge 65 8 of the side panels 7 is preferably formed with a reinforcing rod 9 as indicated in Figures 3 and 5. The upper panels 6 are provided with stationary keepers 10 arranged for cooperative engagement with hood latches 70 11 carried by the side panels 7. These hood latches 11 are preferably fashioned as indicated in the drawing and include a resilient clamping barrel 12 operated by the link lever 75 13. A hood support 14 is formed as a part 80 of the radiator shell 15, and is provided with the usual cushioning band 16. Secured to the underside of the hood support is a stirrup 17 formed with an outwardly and downwardly extending ear or lug 18. This ear 85 18 is adapted to project through suitable openings 19 cut at convenient points in the panels 7, so that when the panel is disposed snugly in place upon its support, the ear 18 is permitted a free passage through the said 90 aperture.

The said stirrup may assume any desired shape. For instance I have illustrated in Figure 5 a plate 20 formed with an integral, curved, outwardly extending lug 21 which, 95 obviously is adapted to serve substantially the same purpose as the straight ear hereinbefore described. In either case a clip 22 may be provided to effect a more pleasing appearance to the exterior of the side panels, as 100

well as to cover the apertures 19 and, moreover, the projecting ear or lug extending therethrough.

In practice, the panel 7 is lowered into position on the side sill or frame member 23 and then slightly raised so as to dispose the said reinforced marginal edge 8 under each projecting ear or lug 18, whereupon when the said latch 11 is operated to clamp the panels 6 10 and 7 together, the side panel 7 being guided bodily inward and locked in fixed position by virtue of the reinforced portion of the said panel being forced tight against the said ear or lug.

15 From the foregoing it will be seen that I have provided a construction, combination and arrangement of various parts which fully attains the objects of the invention hereinbefore set out.

20 Modifications of the above may be made within the spirit and scope of the invention.

What I claim is:

1. In combination with a hood, a support for said hood, a top panel, a removable side 25 panel formed with a bottom reinforcing bead and a pair of apertures positioned immediately above and spaced a small distance from each end of said bead, stationary keepers within the hood comprising downwardly and 30 outwardly projecting lugs, and a pair of latches carried by said side panel for drawing said side panel into cooperative engagement with the top panel, said lugs being arranged to extend freely through said apertures and to engage the bead of said side 35 panel in such manner that the side panel is bodily guided inwardly and snugly seated upon its support, the said side member being positively held there by the said latches.

40 2. In combination with a hood, a support for said hood, a top panel, a removable side panel formed with a bottom reinforcing bead and a pair of openings positioned just above said bead and near the ends thereof, a pair of 45 inclined downwardly projecting keepers mounted on said support and adapted to pass freely through said openings and a latch carried on said side panel for engaging the top panel whereby the said parts of the hood are 50 pulled tightly together and the said bead by its engagement with the said keepers guides the said side panel inwardly into close contact with said hood support.

55 3. In combination with a hood, a support for said hood, a top panel, a removable side panel formed with an aperture near each lower corner thereof, stationary means secured to said support to provide a downwardly and outwardly extending lug adapted 60 to pass freely through each aperture in the side panel, and means associated with the lower marginal edge of the side panel for engagement with the said lug, whereby during 65 the engagement of the said latch with the

top and side panels, the side panel is urged inwardly against the frame of the hood.

In testimony whereof I affix my signature.

FRANK A. WHITTEN.
